UNITED STATES PATENT OFFICE.

HARRY M. MONFORD, OF LEBANON, PENNSYLVANIA.

VAPOR-BATH CABINET.

Application filed December 20, 1922. Serial No. 607,974.

To all whom it may concern:

Be it known that I, HARRY M. MONFORD, a citizen of the United States of America, and a resident of Lebanon, in the county 5 of Lebanon and State of Pennsylvania, have invented a new and Improved Vapor-Bath Cabinet, of which the following is a description.

My invention relates to a cabinet for administering vapor baths such as a medicated vapor and heated vapor medium and more particularly to a cabinet in which the patient may recline with the head protruding from the cabinet.

15 The general object of my invention is to provide a cabinet of the indicated character improved in various particulars with respect to the efficient ventilating and cooling of the cabinet after the bath without unduly subjecting the patient to chilling air and with respect to an arrangement of the piping whereby an increased percentage of heat will be maintained in the region of the feet of the patient.

20 25 The nature of the invention and its distinguishing features and characteristics will more clearly appear as the description proceeds.

Reference is to be had to the accompanying drawings forming a part of this specification, it being understood that the drawings are merely illustrative of one example of the invention.

Figure 1 is a perspective view of a vapor 30 bath cabinet embodying my invention;

35 Figure 2 is a longitudinal vertical section;

40 Figure 3 is a transverse vertical section on the plane indicated by the lines 3—3, Figure 2;

45 Figure 4 is a plan view with the cabinet open.

Generally my improved cabinet embodies the usual feature of a box-like body 10 having suitable supports such as legs 11 and provided with a cover 12 hinged along one edge as at 13. Also, a bottom 14 is provided which inclines in all directions to a central drain cock 15. Similarly, along 50 one side of the cabinet is an upper section 16 hinged as at 17 to be lowered for facilitating the entrance and departure of the patient. A rack or hammock 18 of slats is supported as usual by legs 19 resting on the bottom 14.

55 An opening 20 for the head of the patient

is provided at the head end of the cabinet, and a closure 21 for said head opening 20 is provided and hinged at its lower edge as at 22. In order that the closure 21 may 60 constitute a convenient head rest I provide a support 23 in the form of a diagonal brace hinged at its lower end as at 24 to the body 10. The free end of the brace 23 is adapted to engage in any one of a 65 series of notches 25 on the combined head rest and closure 21 to vary the angular position of said head rest. The brace 23 when disengaged from the head rest 21 drops by gravity to a perpendicular position 70 pendent from the lower edge of the adjacent end of the body 10.

In order to cool the cabinet while the patient is still reclining therein and not subject the patient to chilling air which 75 would result from the raising of the cover 12 a ventilating opening 26 is provided in the cover 12 and adapted to be controlled by a slide closure 27. Similarly, in the opposite sides of the body 10 ventilating openings 28 are formed and controlled by slides 29.

A container 30 of known form may be positioned for holding the sulphur or other medicament, from which container the 80 vapor passes into a perforated pipe 32 ranging lengthwise of the cabinet adjacent the bottom thereof beneath the hammock 18. An air or steam pipe 33 having an inlet funnel 31 leads also into the cabinet 85 and ranges lengthwise thereof. The two pipes 32, 33 connect with a manifold or transverse pipe 34 disposed at the head of the cabinet. From pipe 34 leads a discharge pipe 35 at one end and passes outwardly through the foot of the cabinet between the container 30 and funnel 31. It 90 will be observed that the pipe 33 connects at one end of the cross pipe 34 and the pipe 32 at about the center of said pipe 34 so that the vapors mix and pass along the pipe 35 through the perforations thereof and outward as at 36. The arrangement 95 conveniently separates the container 30 and funnel 31 and the heat is maintained by the pipe 34 beneath the feet of the patient.

I would state in conclusion that while the illustrated example constitutes a practical embodiment of my invention, I do not limit myself strictly to the exact details herein illustrated, since, manifestly, the same can be considerably varied without departure 100 105 110

from the spirit of the invention as defined in the appended claims.

Having thus described my invention, I claim:

- 5 1. A vapor bath comprising a cabinet having a hinged top and a hinged side, openings formed in the sides and in the top, manually-slidable means disposed at the interior of the cabinet for opening or closing said openings, a hammock in said cabinet supported on the bottom of the same, a steam pipe extending within said cabinet between the hammock and the top, a medicament pipe connected with said
- 10 15 steam pipe at their inner ends, an exhaust pipe also connected with said steam pipe

and the medicament pipe, the exhaust pipe and the medicament pipe crossing each other adjacent the foot of the vapor bath to concentrate the heat at the foot of the 20 bath, and a drain cock at the bottom of said cabinet for draining the condensed vapor collected in the bath.

2. In combination with a vapor bath provided with a steam pipe, a medicament 25 pipe and a discharge pipe, of a hammock arranged above said pipes and legs for supporting said hammock extending to the bottom of the vapor bath and across the cabinet and providing openings between 30 the legs through which said pipes extend.

HARRY M. MONFORD.
